UNITED STATES PATENT OFFICE

136,075

DESIGN FOR AN AMPHIBIAN AIRPLANE

Adam J. Stolzenberger, Jr., Glendale, Long
Island, N. Y.

Application December 29, 1942, Serial No. 109,159

Term of patent 7 years

To all whom it may concern:

Be it known that I, Adam J. Stolzenberger, Jr., a citizen of the United States, residing at 78-47 80th Street, Glendale, Long Island, in the county of Queens and State of New York, have invented a new, original, and ornamental Design for an Amphibian Airplane, of which the following is a specification, reference being had to the accompanying drawings, forming a part thereof, wherein:

Figure 1 is a top plan view of an amphibian airplane illustrating the new design, one wing being broken away.

Figure 2 is a side elevational view of the same, the landing gear being shown in extended position.

Figure 3 is a front elevational view of the same, the landing gear being shown in retracted position.

Figure 4 is a bottom plan view of the same, one wing being broken away and the landing gear being shown in retracted position.

I claim:

The ornamental design for an amphibian airplane, substantially as shown.

ADAM J. STOLZENBERGER, JR.
